SOUR-BLUE FORMULATION

William A. Millsaps, Philadelphia, and Julian L. Staubly, Oreland, Pa., assignors to Pennsalt Chemicals Corporation, a corporation of Pennsylvania

No Drawing. Application January 23, 1957
Serial No. 635,620

4 Claims. (Cl. 8—77)

This invention relates to laundry supplies and, more particularly, to improvements in sour-blue formulations.

In commercial laundry operations it is customary to wash the fabric twice with mixtures of soap and alkali, then give a bleaching operation, followed by three or four rinses in water. This usually leaves traces of alkalinity in the fabrics. To neutralize this alkalinity it is customary then to treat the fabric with a sour. It is also customary to treat the fabric with a blue dyestuff to overcome the tendency toward yellowing by enhancing the whiteness. Usually the sour and the bluing operations are combined.

It has been found, however, that sometimes the blue dyestuff does not dissolve, with the result that solid dye particles attach themselves to the fabrics. This results in a blue speck formation, or blue streaks, upon ironing. Various attempts have been made to overcome this blue discoloration, including the use of different dyestuffs, excluding the possibility of contaminants in the commercial sodium fluosilicate, Na_2SiF_6 , etc., but these did not offer a solution.

We have discovered that the off-grade batches of sour-blue formulations contained free acidity, whereas there was no free acidity in good samples, and concluded that this was the result of free acid (i.e., unreacted fluosilicic acid, H_2SiF_6 , or hydrochloric acid formed in the reaction and calculated as H_2SiF_6), in the commercial sodium fluosilicate. In other words, the dyestuff lost its water-solubility from contact with free acid present as contaminant in some batches of the sodium fluosilicate.

We then conceived the possibility of maintaining dye solubility in commercial sodium fluosilicate, even in the presence of small amounts of fluosilicic acid, by the addition of small amounts of sodium carbonate, Na_2CO_3 , and verified this by experiment.

By the term "commercial sodium fluosilicate," as used herein, is meant a sodium fluosilicate which, in the process of manufacture, may contain from 0.0 to 0.15% of free acid calculated as fluosilicic acid.

It is therefore an object of this invention to improve sour-blue formulations.

It is another object to maintain dye solubility in sour-blue formulations containing sodium fluosilicate even in the presence of small amounts of fluosilicic acid.

It is a further object to provide sour-blue formulations which will not cause speck formation and streaking when fabrics treated therewith are ironed.

With the above and other objects in view, which will become apparent as the description of the invention proceeds, we have set forth our invention in the following examples, in which the parts are by weight, which are given by way of illustration and not by way of limitation:

Example 1

	Parts
Na_2SiF_6	100.0
H_2SiF_6	0.1
Na_2CO_3	1.0
Blue Dye-Colour Index 707 (RD-8016)	0.07

The Na_2SiF_6 containing the H_2SiF_6 , or with the H_2SiF_6 added to it, and the Na_2CO_3 are charged into any suitable blending equipment and mixed for at least 5 minutes. The RD-8016 is introduced and mixing is continued for an additional period of at least 6 minutes.

The RD-8016, C.I. 707, is a commercial dye manufactured by New York Color and Chemical Company, New York, N.Y., and is understood to be a sulfonated triphenylmethane.

- 10 The dyestuff in this product was found to be soluble in cold tap water in 14 seconds when tested as follows: Add 0.1 g. H_2SiF_6 to 100 g. of Na_2SiF_6 . Then add the Na_2CO_3 , blend thoroughly, and finally add the dye with further mixing. Test for the time required for the dye to dissolve, when one half g. of the formula is added to 200 mls. of cold tap water. The absence of "comet tails" indicates completed solution of the dyestuff. It has been found that formulations in which all of the dye particles do not dissolve in 60 seconds cause trouble in commercial laundry operations.

When a similar product which contained no Na_2CO_3 was tested under similar circumstances, the dyestuff was completely insoluble in cold tap water.

25

Example 2

	Parts
Na_2SiF_6	100.0
NaHF_2	1.0
Na_2CO_3	2.0
Blue Dye-Colour Index 707 (RD-8016)	0.07

30 These components are mixed in the manner indicated in Example 1, the NaHF_2 being added to the Na_2SiF_6 and Na_2CO_3 .

The dye in this product dissolved completely in 24 seconds when tested as indicated in Example 1.

35

Example 3

	Parts
Na_2SiF_6	100.0
NaHF_2	1.0
H_2SiF_6	g. 0.1
Na_2CO_3	g. 2.0
Blue Dye-Colour Index 707 (RD-8016)	0.07

45 This product made by adding the ingredients in the order indicated, exhibited complete solution of the dye in 37 seconds.

40

Example 4

	Parts
Na_2SiF_6	100.0
H_2SiF_6 (as contaminant)	0.03 to 0.15
Na_2CO_3	2.00
Calcofluor White B concentrate	0.80
Blue Dye-Colour Index 707 (RD-8016)	0.07
Light paraffin oil	0.30

55 These components are mixed in the manner indicated in Example 1, the Calcofluor White and the paraffin oil being added with the dyestuff.

60 When subjected to the test given under Example 1, the dyestuff in this formulation dissolved completely in 30 seconds.

55

Example 5

	Parts
Na_2SiF_6	100.0
H_2SiF_6 (as contaminant)	0.03 to 0.15
Na_2CO_3	2.00
Calcofluor White B conc	0.80
Calcocid Blue 2R	0.08
Light paraffin oil	0.30

65 These components are mixed as in Example 4. The dye dissolved completely in 20 seconds. The Calcocid Blue 2R, C.I. 707, is made by American

Cyanamid Company, New York, N.Y., and is understood to be a sulfonated triphenylmethane.

Example 6

	Parts
Na ₂ SiF ₆	100.0
H ₂ SiF ₆	0.15
Na ₂ CO ₃	3.0
Calcofluor White B Conc.	0.8
Blue Dye-Colour Index 707 (RD-8016)	0.07

These components are mixed as in Example 4. The dye dissolved in 21 seconds.

Example 7

Example 6 was repeated, substituting equal quantities of the alkalis indicated below for the Na₂CO₃, with the satisfactory results, as indicated by the number of seconds required for the dyestuff to dissolve when tested as stated above:

Alkali:	Seconds
K ₂ CO ₃	19
NaOH	14
Na ₄ SiO ₄	13
Na ₂ SiO ₃	15
Na ₄ P ₂ O ₇	20
Na ₂ B ₄ O ₇ · 10H ₂ O	35

Although the preferred alkali is Na₂CO₃, similar but somewhat less satisfactory results, as indicated above, can be obtained by replacing the Na₂CO₃ with K₂CO₃, NaOH, Na₄SiO₄, Na₂SiO₃, Na₄P₂O₇, or Na₂B₄O₇ · 10H₂O, using substantially the same quantities of these other materials. For satisfactory results in the practice of the present invention, the elimination of the blue speck or blue streak formation must last for several months, due to the time which has elapsed while the sour-blue formulation is in storage and the other alkalis indicated have been found to have this property.

The alkalis indicated are preferably used in amount corresponding to 1-3% of the Na₂SiF₆ content although 2% is the preferred quantity, but larger amounts can be used with some sacrifice of the alkali-neutralizing efficiency of the sour-blue.

The H₂SiF₆ is usually present in from 0 to 0.15% based on the Na₂SiF₆ content.

Other dyestuffs found to be adversely affected by H₂SiF₆ when blended in Na₂SiF₆ containing free acidity (up to 0.15%) were:

(1) Amazo Violet 5BS Conc., C.I. 698, New York Color & Chemical Co., New York, N.Y.

(2) Calcocid Violet 4BXL Conc., C.I. 698, American Cyanamid Co., New York, N.Y.

(3) Kiton Fast Violet 4BNS Ex. Conc., C.I. 698, Ciba, New York, N.Y.

(4) Formyl Violet 54BP, C.I. 698, General Aniline & Film Corp., New York, N.Y.

(5) C.P. Soluble Blue, C.I. 707, Imperial Paper & Color Corp., New York, N.Y.

(6) Calcocid Blue B 200%, C.I. 707, American Cyanamid Co., New York, N.Y.

The letters "C.I." refer to a standard color index published by Society of Dyers and Colors, 30 Pearl Assurance Building, Bradford, Yorkshire, England, 1922-24 edition. These letters identify a chemical type rather than a shade.

"C.I. 698" identifies a sodium salt of dibenzyltetraethyl triaminotriphenyl carbinol disulfonic acid anhydride, or of sulfodibenzylidethyldiaminofuchson-diethylimmonium sulfonate.

"C.I. 707" identifies sodium, ammonium or calcium salt of the trisulfonic acid, together with some disulfonic acid, of triphenyltriamino-triphenyl-carbinol anhydride, and of diphenyltriamino-diphenyltolylcarbinol anhydride, or phenyldiaminosulphomethyl-fuchson-sulphophenylimmonium sulfonate.

The dyestuff can be varied according to its strength, but for dyestuffs of the character indicated above the preferred quantities are from 0.05-0.3% based on the Na₂SiF₆ content.

It will be obvious that other components which are customary components of sour-blue formulations may be used and may be added to the above compositions, for example, the optical whitener which may be Calcofluor White B Conc. made by American Cyanamid Company, New York, N.Y., may be used, and the customary amount is 0.8% based on the Na₂SiF₆ content. Similarly, light paraffin oil may be used to prevent dust, and the customary amount is 0.3%.

Generally, the amount of laundry sour-blue added to laundered fabrics is sufficient to lower the pH to 5-6. However, more sour-blue may be used for heavily starched materials like shirts: The amount of sour-blue required to attain the desired lowered pH will vary with efficiency of rinsing operations and alkalinity of the water supply. With low alkalinity water and efficient removal of alkaline detergents, by rinsing prior to souring, one ounce of sour-blue formulation to 100 pounds of fabric is generally sufficient. As much as three or more ounces to 100 pounds of fabric may be required in laundries having high alkalinity water supplies.

It is apparent that many widely different embodiments of this invention may be made without departing from the spirit and scope thereof, and, therefore, it is not intended to be limited except as indicated in the appended claims.

We claim:

1. A laundry sour-blue comprising commercial sodium fluosilicate, a blue dyestuff selected from the group consisting of Blue Dye-Colour Index 707 and Blue Dye-Color Index 698 and 0.1 to 3.0% of an alkali selected from the group consisting of sodium carbonate, sodium hydroxide, sodium orthosilicate, sodium metasilicate, sodium pyrophosphate and sodium tetraborate.

2. A sour-blue having the following composition:

	Parts by weight
Sodium fluosilicate	100.0
Fluosilicic acid (as contaminant)	0.15
Na ₂ CO ₃	1-3
Blue Dye-Colour Index 707	0.05-0.3

45 3. A sour-blue having the following composition:

	Parts by weight
Na ₂ SiF ₆	100.0
H ₂ SiF ₆	0.1
Na ₂ CO ₃	2.0
Blue Dye-Colour Index 707	0.08

4. The method of making a laundry sour-blue, which comprises adding 0.1 to 3.0% of an alkali selected from the group which consists of sodium hydroxide, sodium orthosilicate, sodium metasilicate, sodium carbonate, sodium pyrophosphate and sodium tetraborate to sodium fluosilicate containing as an impurity 0.01 to 1.0% of acidity, calculated as fluosilicic acid, prior to adding a blue dyestuff selected from the group consisting of Blue Dye-Colour Index 707 and Blue Dye-Colour Index 698 to prevent the acidity from destroying the dyestuff and forming blue discoloration on the material laundered upon ironing.
